ELECTRICAL CONNECTING MEANS

Tomun Finizie, Bridgeport, Conn.

Application June 18, 1947, Serial No. 755,321

8 Claims. (Cl. 173—332)

1

This invention relates to electrical connecting means, and is especially applicable to connecting plugs used in connection with flexible conducting cords which supply current to household appliances and the like.

In the use of the appliance, for example an iron, there is considerable wear on the cord due to the flexing or twisting to which the cord is subjected in use, and there is considerable wear on the connector plug due to the strains to which it is subjected.

One of the objects of the invention is to reduce the wear on the cord and on the connector plug, and to provide a connection between the cord and plug which will withstand heavy pulling strains without injury and relieve the strains on the plug.

Another object is to provide a connecting plug or like member connected to a cord or cable in a manner to prevent sharp bending of the electrical conductors in places near the region where the cord or cable enters the plug, and a further object is to provide a structure in which the user of the article will in most cases detach the cord by manipulation such that the cord will have a long life.

In the the accompanying drawings:

Fig. 1 is a face view of a connecting plug embodying the invention;

Fig. 2 is an edge view;

Fig. 3 is a view similar to Fig. 1, showing one of the casing sections removed;

Fig. 4 is an enlarged view of the upper part of Fig. 3, certain parts being shown in section;

Fig. 5 is a section on line 5—5 of Fig. 4;

Fig. 6 is a section on line 6—6 of Fig. 4;

Fig. 7 is a section on line 7—7 of Fig. 4;

Fig. 8 is a detail face view of the swinging or rocking member of the plug, the electrical connections being omitted;

Fig. 9 is an end view of the member just referred to; and

Figs. 10 and 11 are detail views showing one of the wire coils used in the plug.

In the form shown in the drawings, the connector plug has a generally rectangular and flattened casing constructed in two sections, and provided within the lower part with contact terminals which are of hollow form so as to receive the connecting prongs provided on the electrical appliance, for example a pressing iron. The plug also comprises in its structure a swinging member having a pivot pin received within a hollow top portion with which the casing is provided, said pivot pin being joined rigidly to a part in the

2

nature of a handle projecting to the outside of the casing and operating in a cut-away portion or recess in the top of the casing, which cut-away portion or recess is adapted to limit the movement of the movable member in the manner hereinafter described. The exteriorly projecting part or handle on the movable member is hollow so as to receive the conductor cord, and the conductor cord enters the plug through this part, and has its individual wires separated in a location within the casing, the separated wires being attached to the pivot pin, and suitable electrical connections being provided between these wires and the stationary contact members within the lower part of the casing, so that the movable member of the plug can have swinging movement in the use of the plug without subjecting the terminal members of the plug to strain or injury. The separated wires coming from the cord pass through openings provided within the pivot pin and are held in place by means such as screws that are carried by the pivot pin and are readily accessible, and these screws are respectively connected with the lower terminals of the plug by wires in the form of coils, the coils being in embracing relation to the ends of the pivot pin, and said coils providing a satisfactory form of flexible connection between the terminals and the swinging or rocking member of the plug. The latter member reduces the strains on the device in the manner hereinafter described.

In the drawings, the casing is indicated at 20, the conductor cord at 21, the swinging member pivotally mounted in the casing at 22, said member having the pivot pin 23 and the handle 24, and having the longitudinal bore 25 receiving the conductor. The portion of casing 20 which receives the pivot pin is indicated at 26, and the opening in the top portion of the casing through which handle member 24 projects is indicated at 27. One of the sections of the casing is indicated at 28 and the other at 29, these sections being interconnected by screws 30. The socketed terminals in the lower part of the casing are indicated at 31 and 32, these being connected respectively to the wire coils 33 and 34, and said coils being respectively connected to screws 35 and 36 that are screwed into sockets in the pivot pin and are respectively connected to the wires 37 and 38 branched off from the cord. The wire coils 33 and 34, as shown in Fig. 6, are disposed around the end portions of the pivot pin.

Referring to the details, the casing 20 is generally shallow and flat, and has the elongated tubular upper part 39 receiving the pivot pin 23,

the latter being cylindrical and adapted to turn within the casing portion 39 on an axis disposed transversely of the casing, the arrangement being such that the handle member 24 can move in a plane generally perpendicular to the plane of the casing, but to a limited extent only, this movement being limited by the edges of the aperture 27. As shown in Fig. 1, the width of the aperture 27 is such as to prevent any substantial movement of the handle member 24 longitudinally of the axis of the pivot pin, but, as shown in Fig. 2, the handle member can swing forwardly or rearwardly to a position in which it is at an acute angle to the general plane of the casing, being capable of a movement from the position shown in full lines in Fig. 2 to the position shown in dotted lines, and in each case being limited from further movement by the side surface of the handle member coming up against the curved edge of the aperture 27. It will be noted, further, that in the form shown the handle member 24 extends from the pivot pin to a considerable degree, or, in other words, has considerable length, this being useful in avoiding any sharp bend in the conductor cord. Moreover, for the latter purpose the free end of the handle member is preferably made bell shaped, as shown at 40, the bell-shaped end having a flared inner surface 41 so that the cord entering the handle member, if bent or deflected to one side, will necessarily take a gradual curve corresponding to the gradual curve on the inner surface of the mouth or funnel of the handle.

The bore 25 in the handle member leads to longitudinal passages 42, 43 extending transversely through the pivot pin and receiving the individual wires of the cord, which wires pass down to cut-out portions in the lower part of the pivot pin, and are then led forwardly and upwardly so as to have their end portions arranged under the heads of the clamping screws, as shown in Fig. 7. Clamping screw 35, for example, as shown in Fig. 7, has a head 44 disposed in a socket 45 at the forward part of the pivot pin, and the screw has a threaded shank 46 passing through a hole provided within the pivot pin and disposed transversely with respect to the pivot pin. The end of the threaded shank 46 is screwed into a threaded socket 47 provided in a small metal plate or clip 48, said plate or clip having a clinched-over end portion 49 clinched on one terminal portion of the wire coil 33. It is understood that the structure of the device adjacent the two ends of the pivot pin is the same, and the structure adjacent the right-hand end (Fig. 4) of the pivot pin is now being described by way of example. One end of the coil 33 is attached to the small plate 48, as above indicated, and the opposite end of the coil is connected as by clinching to the upper end portion of the terminal 31, and in this instance such upper end portion has a sheet metal portion 50 clinched about the wire. The clinched connection 49 is disposed exteriorly of the pivot pin body adjacent the end of the pivot pin, as shown in Fig. 6, and the body of the plate 48 is introduced into a slotted portion 51 in the pivot pin, which slotted portion provides a seat for the plate 48, as shown in Fig. 7, in which seat the plate 48 is held by the clamping screw.

The wire coil 33 is disposed adjacent one end of the pivot pin, and is disposed in embracing relation to a part of the pivot pin, for which purpose the pivot pin is provided with an extension 52 in the form of a rib that is of less diameter than the pivot pin body. This extension 52 en-

ters the wire coil 33 and serves to center and seat the wire coil, the external surface of which lies in substantial contact with the casing, the casing, of course, being of suitable insulating material. The extension 52 is generally C-shaped, the gap in the extension being located at the upper forward side (Figs. 4 and 5), so as to facilitate the introduction of the plate 48 into the slotted portion 51. That end of the coil 33 which is disposed toward the middle of the pivot pin is connected to the plate 48, whereas the other end of the coil, which is located beyond the end of the pivot pin, is connected to the terminal 31.

The individual wires from the conductor cord, 15 in passing from the ducts or passages 42, 43 to clamping seats at the forward portion of the pivot pin, are extended over a part of the periphery of the pin, and this obviously is of assistance in relieving strain in the connections between 20 the wires and the pivot pin. The helical coils of wire arranged between the pivot pin and the terminals obviously prevent strain between the plates or clips such as 48 and the terminals. The plug can, therefore, stand a large amount of 25 tension applied to the conductor cord without injury to the connections within the plug. Moreover, the conductor cord, even if frequently flexed or bent in the use of the electrical appliance, will not be bent adjacent the connector 30 plug in a manner which can injure the cord, owing to the fact that any bending in the region where the cord enters the plug is necessarily on a gradual curve. Moreover, the present invention enables the cord angle to adjust itself to a 35 certain extent with reference to the plug, owing to the movability of the externally projecting member of the plug with reference to the general plane of the casing, because this will in many cases obviate the need of bending the cord adjacent the mouth portion of the handle member. It will be apparent from Fig. 2 that the swinging of the cord-positioning external member to an inclined position with reference to the plug body or casing will reduce the angularity of the 45 incoming cord, and thereby reduce strain and tension on the cord, with the accompanying harmful effects.

A further advantage of the article arises from the fact that a substantial handle portion is 50 provided upon the plug, the arrangement being such that the user, in disconnecting the plug, will grasp the handle rather than the cord, thereby obviating the strain on the conductor and its connections. The clamping screws or binding screws 55 provided on the pivoting portion of the movable member are located in a manner to relieve strain on the wires of the conductor. The wire coils obviously provide a flexible and movable means connecting the plate members such as 48 to the 60 terminal members in the lower part of the casing. The binding screws, moreover, serve a double function, in that they fix the divided wires of the cord in position, and connect those wires electrically in an effective manner with the connecting wires or conducting means intermediate 65 the terminals and the binding screws, and thus the number of separate parts employed in the manufacture of the article is reduced.

It will be manifest from the foregoing description 70 that the device illustrated comprises a connector body having terminals adjacent one end housed in the body, and having the swiveling socket interiorly disposed and located toward the other end of the body, said socket receiving a two-part member, one of the parts of said member

being a pivoting or swiveling element and the other part being a cord-positioning element at right angles to the swiveling element and adapted to enclose a cord having a strain-relieving connection to the swiveling member, the swiveling member being connected to the terminals by flexible wires or elements, which in part are disposed exteriorly of the swiveling member and in part interiorly thereof, the swiveling member being equipped with binding members that bind the led-in wires from the cord, and likewise form electrical conductors conveying current from the cord to the conducting members that are connected to the plug terminals.

Only one form of the invention is shown herein, but it is understood that this is by way of example only, and that various modifications and changes may be made without departing from the principles of the invention or the scope of the claims.

What I claim is:

1. A device such as described, comprising a body part having a pair of fixed engageable contact terminals enclosed therein, a handle member associated with said body part and having as a part thereof a pivot member socketed and movable in said body part, the conductors extending through said handle member and strain-relief passages in the pivot member, and means for connecting said conductors with said contact terminals, said last-named means including flexible coils located exteriorly of and adjacent the ends of said pivot member and extending thence to said terminals.

2. A device such as described, comprising a generally planar body made up of separable front and rear sections and having a pair of engageable contact terminals enclosed within the lower end portion thereof, said body having a socket adjacent the upper end thereof located interiorly of the body and in communication with an aperture leading to the exterior of the body at the upper part thereof, a handle member having a pivot pin located in said socket to swing therein in a plane substantially perpendicular to the general plane of the body and having a tubular neck projecting exteriorly from the body through said aperture and receiving a conductor cord, said conductor cord being divided within the body and having separate wires passing through strain-relief passages, and binding members securing said separate wires to said pivot pin and having manipulating heads at the exterior of the pin, said binding members also securing conducting means exteriorly of the ends of the pivot pin, said conducting means including flexible wire coils connecting said binding members with said contact terminals.

3. A connector plug having a body equipped interiorly adjacent one end with fixed contact terminals and having in association with the other end a cord-guiding member mounted for limited swinging movement, said cord-guiding member comprising a swiveling pin portion mounted in a crosswise socket in the body and also comprising an exteriorly projecting cord-guiding portion, said cord-guiding portion being hollow and accommodating a cord comprising two conductors, said conductors being separated from each other and extending through strain-relief passage means in the swiveling pin portion and fixedly mounted at their ends with respect to said pin portion by binding screws, and flexible conductor members extending exteriorly and longitudinally of said pin portion and presenting

75 a series of loops, said flexible electrical conductor members connected to said binding screws and to said terminals and providing strain-relief connections between the movable swiveling pin portion and the terminals.

4. A connector plug having a body equipped interiorly adjacent one end with terminals and having in association with the other end a cord-guiding member mounted for limited swinging movement, said cord-guiding member comprising a swiveling pin portion mounted in a crosswise socket in the body and also comprising an exteriorly projecting cord-guiding portion, said cord-guiding portion being hollow and accommodating a cord comprising two conductors, said conductors being separated from each other and extending through passage means in the swiveling pin portion and fixedly mounted at their ends with respect to said pin portion by binding screws, and flexible electrical conductor members connected to said binding screws and to said terminals and providing strain-relief connections between the movable swiveling pin portion and the terminals, said last-named conductor members comprising coils associated with the respective ends of said swiveling pin portion and in embracing relation to said portion.

5. A device such as described, comprising a sectional flat substantially rectangular body having a pair of engageable contact terminals enclosed within the lower part and having at the upper part a rounded hollow enlargement extending from edge to edge, a handle member associated with said body part and having as a part thereof a pin or barrel member mounted within said enlargement for tilting movement therein and also comprising as a part thereof an exteriorly projecting cord-guiding member of hollow formation having a funnel-shaped outer end, said body part having an aperture at the upper end through which said last-named member protrudes, the aperture being located in the upper wall of the body adjacent the juncture of said last-named member with said pivot pin member and being formed to permit a limited tilting movement of said handle member, a cord extending through said handle member and having separated conductor portions extending through strain-relief portions and secured to said pin member, and means for flexibly connecting the secured ends of said separated conductor portions electrically to said contact terminals, said means being associated with and embracing the outer end portions of the pin member.

6. A device such as described, comprising a body part having a pair of engageable contact terminals enclosed therein, a handle member associated with said body part and having as a part thereof a pin member extending crosswise with respect to said body part and socketed therein and also having as a part thereof an exteriorly protruding cord-guiding part perpendicular to the pivot pin, the cord-guiding part being hollow and accommodating a cord and the pin having passages accommodating spaced apart conductor members of the cord, binding screws securing the ends of said spaced conductor members to said pivot pin, and conductor members having as integral parts thereof coils associated with the ends of the pivot pin for connecting said binding screws with said contact terminals.

7. A device such as described, comprising a body part having a pair of engageable contact terminals enclosed therein, a handle member

associated with said body part and having as a part thereof a pin member extending crosswise with respect to said body part and socketed therein and also having as a part thereof an exteriorly protruding cord-guiding part perpendicular to the pivot pin, the cord-guiding part being hollow and accommodating a cord and the pin having passages accommodating spaced apart conductor members of the cord, binding screws securing the ends of said spaced conductor members to said pivot pin, and conductor members having coils associated with the ends of the pivot pin for connecting said binding screws with said contact terminals, said coils embracing the end portions of said pin, and said binding screws having heads located adjacent the outer surface of said pivot pin.

8. A device such as described comprising a body part having a pair of engageable contact terminals enclosed therein, a handle member associated with said body part and having as a part thereof a pivot member socketed and mov-

able in said body part, conductors extending through said handle member and through strain-relieving portions in the pivot member and attached by means of binding screws to the last-mentioned member, and means for connecting said conductors with said contact terminals, said means including flexible members located exteriorly and longitudinally of said pivot member and presenting a series of loops of wire.
